(57) **CLAIM**

The ornamental design for a double-sided hanging beverage holder, as shown and described.

DESCRIPTION

FIG. 1 is a perspective view of my new design for a double-sided hanging beverage holder;

FIG. 2 is a right-side elevation view thereof;

FIG. 3 is a left-side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines in the drawings are included for the purpose of illustrating environmental subject matter and form no part of the claimed design.
